UNITED STATES PATENT OFFICE

159,282

MAGNETIC TAPE RECORDER

Frank Lustig, Chicago, Ill., assignor to Revere Camera Company, Chicago, Ill., a corporation of Delaware

Application December 22, 1949, Serial No. 6,774

Term of patent 14 years

(Cl. D26—14)

To all whom it may concern:

Be it known that I, Frank Lustig, a citizen of the United States, residing at Chicago, State of Illinois, have invented a new, original, and ornamental Design for a Magnetic tape recorder, of which the following is a specification, reference being had to the accompanying drawing, forming a part hereof.

The single figure is a perspective view of a magnetic tape recorder showing my new design.

The dominant features of my design reside in that portion shown in full lines on the drawing.

I claim:

The ornamental design for a magnetic tape recorder, as shown and described.

FRANK LUSTIG.
